UNITED STATES PATENT OFFICE.

JAMES W. GRAHAM, OF ST. LOUIS, AND CHARLES A. JONES, OF MIDLAND, MISSOURI.

CONCRETE ASH-PIT.

No. 881,678.

Specification of Letters Patent. Patented March 10, 1908.

Application filed June 3, 1907. Serial No. 376,896

To all whom it may concern:

Be it known that we, JAMES W. GRAHAM and CHARLES A. JONES, both citizens of the United States, and residents of St. Louis, Missouri, and Midland, St. Louis county, Missouri, respectively, have invented certain new and useful Improvements in Concrete Ash-Pits, of which the following is a specification containing a full, clear, and exact description, reference being had to the accompanying drawings, forming a part hereof.

Our invention relates to an ash pit, or receptacle, our object being to construct an ash receptacle of concrete, or analogous plastic material, which receptacle is very strong and durable, thoroughly fireproof, and cheap in manufacture.

A further object of our invention is to construct an ash pit, or receptacle, of concrete, or analogous material, and arrange the same on a suitable base embedded in the ground; and provide the pit, or receptacle, with a smooth interior surface, and with a horizontally corrugated exterior surface, thereby providing an extraordinarily strong construction, and at the same time producing a neat and finished appearance.

To the above purpose, our invention consists in certain novel features of construction and arrangement of parts, which will be hereinafter more fully set forth, pointed out in the claims, and illustrated in the accompanying drawings, in which:

Figure 1 is a perspective view of an ash pit; Fig. 2 is a vertical section taken on the line 2—2 of Fig. 1; Fig. 3 is a plan view of the forms in which our improved ash pit is produced; Fig. 4 is a vertical section taken on the line 4—4 of Fig. 3.

In the construction of our improved ash pit, we form a foundation in the ground, which foundation is composed of a body 1, of cinders, or analogous material, on top of which is located a layer of concrete 2.

The forms in which the wall of the receptacle is formed are now positioned on top of the foundation, the inner form comprising a plurality of vertically disposed plates 3, having smooth surfaces, and the ends of said plates being detachably joined by bolts 4. The outer form comprises a plurality

of sheet metal members 5, which are corrugated horizontally, and the ends of said plates being detachably connected by bolts 6. 55

The forms so constructed are concentrically arranged, and the concrete in plastic form is poured into the space between the walls of the form; and, after the concrete has become thoroughly hardened, the forms 60 are removed by detaching the bolts at the ends of the various sections, and the pit, or receptacle, comprising the vertically disposed wall 7, having the rounded ends 8, with the smooth interior surface 9, and the 65 horizontally corrugated surface 10, is completed. The lower end of the wall 7 forms a bond with the concrete base 2, and thus the pit or receptacle is rigidly positioned. The smooth interior surface of the pit permits a shovel, or like tool, to be readily used in removing the contents of the pit, and the horizontally corrugated exterior surface of the wall 7 gives great strength to the pit, prevents the same from cracking, and presents a neat and finished appearance. Pits, or receptacles, so constructed are cheap, 75 thoroughly fireproof, and practically indestructible.

We claim:

As a new article of manufacture, an ash pit, constructed in a single integral piece and formed of hardened plastic material and comprising a pair of vertically disposed parallel side walls 7, the semi-circular end walls 8 connecting the ends of the side walls, the inner surfaces of which side and end walls are smooth and the exterior surfaces of said walls being provided with the horizontally disposed parallel corrugations 10, a base 2 90 of plastic material imbedded in the ground, the top of which base is of greater width than is the thickness of the wall of the ash pit, and the ash pit being bonded to the base at the time of its formation, and a sub-base 1 95 granular material, supporting the base.

In testimony whereof, we have signed our names to this specification, in presence of two subscribing witnesses.

JAMES W. GRAHAM.
CHARLES A. JONES.

Witnesses:

EDWARD E. LONGAN,
M. P. SMITH.
